POWER OPERATED HANDSAW

Original Filed Jan. 3, 1921 2 Sheets-Sheet 2

UNITED STATES PATENT OFFICE.

RAYMOND L. BARKER, OF CHICAGO, ILLINOIS.

POWER-OPERATED HANDSAW.

Application filed January 3, 1921, Serial No. 434,538. Renewed July 19, 1923.

To all whom it may concern:

Be it known that I, RAYMOND L. BARKER, a citizen of the United States, residing at Chicago, in the county of Cook and State of Illinois, have invented a certain new and useful Improvement in Power-Operated Handsaws, of which the following is a full, clear, concise, and exact description, reference being had to the accompanying drawings, forming a part of this specification.

This invention relates to power-operated hand saws, and more specifically to power-operated hand saws having guards adapted to protect the saw blades.

An object of my invention is to provide a power-operated hand saw having a guard for the saw blade thereof, the guard being adapted to be displaced from its protecting position when the saw is brought into operative relation with the work.

Another object of my invention is to provide a saw of the class described having a saw blade guard which is adapted to be collapsed by engagement with the work.

A further object of my invention is to provide a saw of the class described, having a saw blade guard adapted to bear upon and be displaced by the work, the guard comprising an anti-friction device, which contacts with the work.

These and other objects of my invention will be more clearly pointed out as the following description progresses, reference being had to the accompanying drawings, wherein

Figure 1 is a central longitudinal section of my improved power-operated hand saw.

Figure 2 is a plan view of my improved power-operated hand saw, a cover plate being removed for the purpose of clearer illustration.

Figure 3 is a sectional view taken on line 3—3 of Figure 1, looking in the direction of the arrows.

Figure 4 is a fragmentary central longitudinal section showing a modified form of my invention.

Figure 5 is an end elevation of the modified form of my invention shown in Figure 4.

Figure 6 is a sectional view taken on line

6—6 of Figure 4, looking in the direction of the arrows.

Figure 7 is an enlarged fragmentary sectional view taken on the same line as Figure 55 4, but showing certain details in section which are shown in elevation in Figure 4.

Figures 8 and 9 are detailed views illustrating the manner in which my invention may be applied to a power-operated file or 60 hack saw.

Similar characters of reference indicate similar parts throughout the several views.

Referring to Figure 1, the reference character 10 designates the casing of my improved power-operated hand saw, the saw blade being indicated at 11. The casing 10 preferably comprises two members 12 and 13 secured to each other by bolts 14, the members 12 and 13 being adapted to form a hollow handle 15, and a chamber 16. Disposed in the chamber 16, and rigidly secured to the members 12 and 13 by bolts 17 is an electric motor 18. Energy is supplied to the motor 18 by a conductor 19 originating at 75 any suitable source of power. The conductor 19 enters the handle 15 at its lower end. A switch 20 conveniently disposed in the handle 15 is placed in series with the motor to provide means whereby the operation of 80 the device may be controlled. Bearings 22 and 23 formed integrally with the members 12 and 13, a half of each bearing being a part of each of the members, rotatably journal the motor shaft 24. Keyed to the upper 85 end of the shaft 24 is a crank plate 25, having a crank pin 26. One end of a crank arm 27 is pivotally secured to the crank pin 26, the other end being pivotally connected to a rod 28 by a pin 29. The rod 28 is slidably 90 journaled in a bearing portion 30 extending from and formed integrally with the casing member 12. It is apparent that the motor 18 when in operation will reciprocate the rod 28 by means of the crank plate 25, the crank 95 pin 26 and crank arm 27. As shown in Figure 3, the rod 28 is preferably rectangular in cross section to insure alignment of the several enumerated parts. In my preferred construction, a bushing 32 of suitable material is disposed in the bearing portion 30, the bushing 32 being adapted to journal the

- rod 28. The casing 10 is provided with a removable cover plate 33.
- To secure the saw blade 11 to the rod 28, the outer end of the rod 28 is flanged as at 35. A coupling 36 having an aperture 37 shaped to conform to the rectangular cross section of the rod 28 is adapted to be drawn upon the rod 28, and to rest against the flange 35. Rigidly secured to the inner end 10 of the saw blade 11 by rivets 39 is a plug 40, which is threaded into the coupling 36. This construction permits adjustment of the blade 11 relatively to the plane of rotation of the crank plate 25, as the plug 40 need not draw 15 the coupling 36 tightly against the flange 35. It also permits the alternate use of cross cut and rip saw blades, as well as the use of other tools which are illustrated in the drawings, and hereinafter described.
- 20 The saw blade 11 is protected from injury by a guard 45 comprising a cylindrical tube 46 rigidly secured to a flange 47 of the bearing portion 30. The tube 46 is disposed around the outer end of the bearing portion 25.
- 30 A plurality of tubes indicated at 48, 48^a, 48^b, and 48^c are adapted to successively telescope within one another, the tube 48^a telescoping within the tube 48, on so on. The tube 48 is adapted to telescope within the tube 46. Means comprising compression springs 49, 49^a, 49^b and 49^c are provided for holding the tubes in an extended position relatively to each other, the springs tending to force the tubes apart along their 35 several axes, which are substantially coincident. The springs 49, 49^a, 49^b, and 49^c are disposed around the tubes 48, 48^a, 48^b, and 48^c respectively. Each of the tubes 46, 48, 48^a, and 48^b is provided at its outer end with 40 an inwardly extending flange 50 which serves to retain a ring 51 interposed in each instance between the larger and smaller tubes of any pair of immediately associated tubes. Each ring 51 functions to guide the 45 smaller tube and to stop a similar ring 52, rigidly secured to the smaller tube. Each of the springs 49, 49^a, 49^b and 49^c has one end resting against a ring 52, and the other against a similar ring 53 disposed inside 50 of the larger tube of its associated tubes, and slidably journaling the smaller tube. A plurality of fingers 54 projecting inwardly from the walls of the outer tubes serve to prevent longitudinal displacement of the 55 rings 53 by the several springs. It is readily understood that each of the springs forces the tube about which it is wound in an outwardly direction, the rings 51 limiting the movement of the tubes in this direction. In 60 their extended position, the tubes are adapted to protect the saw blade from injury, and also to prevent injury to the operator when the blade is reciprocating, but not in actual use.
- 65 The outer end of the tube 48^c, which oc-

cupies the most extended position relatively to the casing 10 is provided with an outwardly extending flange 55. The flange 55, co-acting with a ring 56, disposed around the tube 48^c, retains and journals a plurality 70 of metallic balls 57.

As the several tubes enclose the saw blade, the balls 57 will engage any work with which the saw is brought into operative relation. The operator will apply a comparatively 75 light pressure in a longitudinal direction relatively to the saw blade, and the several springs will permit the tubes to telescope within one another, thereby unsheathing the blade. However, one or more of the balls 80 will remain in contact with the surface of the work, and lessen the friction between the casing and the work as the operator guides the saw blade.

In Figures 4, 5, and 6, I have illustrated 85 a modified form of my invention, in which a guard is provided for the saw blade 11, but does not completely encircle it. A bearing portion 30^a, a rod 28^a, and coupling means whereby the saw blade 11 is secured 90 to the rod 28^a are shown, the several parts being similar in detail to the respective parts of the preferred form of my invention. A pair of sleeves 60—60 disposed around and secured to the bearing portion 30^a by screws 95 61 are provided with a pair of inwardly extending flanges 62—62 which co-act with a U-shaped bar 63. A bolt 64 is adapted to draw the U-shaped bar 63 tightly against the flanges 62—62, and lock the bar in any 100 desired position. The purpose of this construction will presently appear.

The guard in the modified form of my invention comprises a plate 65 having one of its ends interposed between the head of the bolt 64 and the peripheries of the sleeves 60—60, the plate 65 being apertured to permit the shank of the bolt 64 to pass through it. Referring to Figures 5 and 6 it will be noted that the plate 65 is provided with a 110 pair of inwardly extending side flanges, 66—66, which converge toward each other, and toward the saw blade 11. At this point in the description, it is well to point out that if the blade 11 is adjusted about the axis of the rod 28^a, and therefore relatively to the plane of its associated crank plate (not shown), the plate 65 may be adjusted by means of the bar 63, and the bolt 64, to occupy the same position relatively to the 115 blade as is shown in the drawings. This will permit the plate 65 and its hereinafter described associated plates 69, 69^a, 69^b and 69^c to be adjusted to protect the blade at any angle to which it is adjusted. The above-mentioned plates are similar in form to the plate 65, and each is provided with side flanges similar to the side flanges 66—66 of the plate 65. The plate 69 with its flanges 120 is adapted to telescope within the plate 65 130

and its flanges 66. The remaining plates and flanges are likewise adapted to successively telescope within one another. The plates are normally forced apart in a longitudinal direction by compression springs 70, a plurality of springs 70 being provided for each plate with the exception of the plate 65, which is secured to the sleeves 60—60. Each of the plates 65, 69, 69^a and 69^b is provided with a bar 71, shaped to conform with its inner surface, each bar 71 being secured to the outer end of its associated plate by rivets 72. Each bar 71 guides the inner plate of each immediately associated pair of plates, and stops a similar bar 73 secured to the outer side of the inner plate. One end of each spring 70 rests against a bar 73, the other end resting against a similar bar 75 rigidly secured to the outer plate of each pair of plates. The plate 69^c is provided with balls 76, which function as do the balls 57 of the preferred form of my invention.

In Figure 7 I have illustrated the manner in which I prevent the springs 70 from buckling. Projecting from each bar 73 is a rod 73^a adapted to telescope into sleeves 75^a carried by each bar 75. The springs 70 are disposed around each pair of sleeves 75^a and rods 73^a.

30 With the exception of the adjustable feature of the guard relatively to the edge of the saw blade 11, a guard of the modified form of my invention functions similarly to a guard of the preferred form.

35 Figure 8 shows a file provided with a plug 40^b, adapted to be threaded into the coupling 36 of the preferred form of my invention. The file when so attached to the coupling may be reciprocated, and will be protected

40 from injury when not actually in use.

Figure 9 illustrates a hack saw provided with a plug 40^c, adapted to be threaded into the coupling 36. The full lines show a hack saw frame suitable for use with the guard, having plates which do not encircle the saw blade. The hack saw frame may be of the proportions indicated in the dotted lines, thereby permitting the guard to be constructed of a plurality of tubes.

50 While I have described the details of but two forms of my invention, it is to be understood that my invention is not limited to these details except by the scope of the appended claims.

55 What I claim is:

1. A portable power-operated and hand-manipulated and applied tool comprising a reciprocating blade adapted to be advanced endwise of the blade toward a surface of the work, the blade having a longitudinal side-cutting edge in combination with a guard normally enclosing the entire length of the side edge and so mounted that upon engagement with the work it may yield longitudinally of the blade to expose the cutting edge

to the extent to which said edge penetrates the work.

2. A power-operated hand-manipulated tool comprising a reciprocating blade adapted to be advanced endwise of the blade towards a surface of the work, the blade having a longitudinal side cutting edge in combination with a guard normally enclosing the entire length of the side edge and so mounted that upon engagement with the work it may yield longitudinally of the blade to expose the cutting edge to the extent to which said edge penetrates the work.

3. A power-operated hand-manipulated tool comprising a reciprocating blade adapted to be advanced endwise of the blade toward a surface of the work, the blade having a longitudinal side cutting edge in combination with a guard normally enclosing the entire length of the side edge, said guard comprising a plurality of telescopic sections and springs operating on said sections to normally force them outwardly from said casting, said guard being so mounted that upon engagement with the work said sections may yield longitudinally of the blade to expose the cutting edge to the extent to which said edge penetrates the work.

4. A unitary portable power operated hand manipulated saw, including a frame carrying saw driving mechanism, a reciprocating saw blade having a longitudinal side cutting edge adapted to be advanced endwise of the blade toward a surface of the work, in combination with work engaging means carried by said frame and adapted to act between said frame and the work to support the tool by the work while the blade is reciprocating.

5. In a unitary portable power-operated saw, the combination of a frame, a handle portion for holding said frame, a reciprocating saw blade having a longitudinal side cutting edge, a rotary member journalled in said frame, a crank driven by said rotary member, a reciprocating member connecting said crank with said saw blade, means for guiding said saw blade in its reciprocating movement, a work-engaging member movably supported on said frame, and spring means tending to hold said work-engaging member with the end thereof in proximity to the end of said saw blade, said spring permitting the end of said work-engaging member to move away from the end of said saw blade during the cutting operation, said work-engaging member thereby yieldingly supporting the tool on the work.

6. In a unitary portable power-operated saw, the combination of a frame, a rotary member journalled in said frame, a saw having a longitudinal side cutting edge, said saw having guided support in said frame for longitudinal reciprocation, transmission means for translating the rotary motion of

4
said rotary member into reciprocating motion for said saw, a work-engaging member movably supported on said frame, and spring means normally moving said work-engaging member into proximity to the end of said saw, said spring means cooperating with said work-engaging member to resiliently support said frame on the work and

permitting said member to recede from the end of said saw.

10

In witness whereof, I hereunto subscribe my name this 30th day of December, 1920.

RAYMOND L. BARKER.
